(57) **CLAIM**

The ornamental design for a car mount phone holder with hooks as shown and described.

DESCRIPTION

FIG. 1 is a perspective view of a car mount phone holder with hooks showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the car mount phone holder with hooks where the car mount phone holder with hooks is in a configuration of use.

The broken lines in the drawings depict portions of the car mount phone holder with hooks that form no part of the claimed design.
